J. F. MacKAY,
VAPORIZED OIL BURNER.
APPLICATION FILED OCT. 10, 1916.

Patented May 14, 1918.

Inventor
John F. MacKay
By his Attorney
Fred A. Wacker.

UNITED STATES PATENT OFFICE.

JOHN F. MACKAY, OF BORDENTOWN, NEW JERSEY.

VAPORIZED-OIL BURNER.

1,266,295.

Specification of Letters Patent. Patented May 14, 1918.

Application filed October 10, 1916. Serial No. 124,767.

To all whom it may concern:

Be it known that I, JOHN F. MACKAY, a citizen of the United States, and resident of Bordentown, in the county of Burlington and State of New Jersey, have invented certain new and useful Improvements in Vaporized-Oil Burners, of which the following is a specification, reference being had therein to the accompanying drawing.

- 10 My invention relates to a burner wherein coal oil, kerosene, gasoline, or any other hydrocarbon or similar oil or liquid is vaporized and burned. The object thereof is to provide simple and effective means for carrying the purpose of the invention into effect. One of the chief features in the construction and arrangement of the mechanical features is a series of two or more chambers that are highly heated and through which the vapor from the oil passes with an increasing degree of fineness or attenuation so that the vapor may be said to be superheated one or more additional times after the first vaporization in the first chamber in order that it may be more effective for use in producing a strong and vigorous lighting and heating quality; and further, the invention may be said to comprise numerous details and peculiarities in the construction, arrangement, and combination of the various parts, substantially as will be hereinafter described and pointed out in the ensuing clauses of claim.

In the accompanying drawing illustrating my invention:

Figure 1 is a vertical section of my improved vaporized oil burner.

Fig. 2 is another vertical section taken at right angles to the section of Fig. 1.

Fig. 3 is a top plan view of my improved burner.

Fig. 4 is a horizontal section of my improved burner.

Similar characters of reference designate corresponding parts throughout the different figures of the drawing.

1 denotes an oil supply pipe for bringing oil to the burner from any suitable source, as, for instance, the tank or pressure chamber. The oil or liquid which is employed may be any vaporizable substance such as coal oil, kerosene, gasoline, and the like, as my invention is not limited to any particular substance but can be employed with any oil

which will volatilize and pass into an inflammable vapor. Pipe 1 opens into a bow-shaped or forked pipe 3 whose upright parallel branches enter and support the top mechanism of the burner, the immediate entry of the said sections of the pipe 3 being into a chamber 4 which is a circular passage in a horizontal casting 20, in which casting is also an inner concentric circular passage 5 with which chamber 4 communicates through lateral openings 6 in the wall intervening between the two chambers 4 and 5.

On the supply pipe 1 or at some suitable point below the bifurcated pipe 3 and below the other parts of the burner is a priming cup 2 consisting of a suitable shallow member designed to receive a certain amount of inflammable oil or other fluid which can be ignited for the purpose of assisting in the initial vaporization of the oil passing upward from the pipe 1 through the pipe 3 in order that pipe 3 and the other parts may be heated very hot at the beginning so that the oil will quickly volatilize.

Suspended from the chamber 5 by being attached at two points to the casting 20, at which two points communication is made with said chamber 5, is a curved or bow-shaped pipe 7 which preferably lies within the same plane as the forked or bow-shaped pipe 3 and which has the same general curvature as said pipe 3 (see Fig. 1). It should be noted that while the passage of the oil and vapor through the pipe 3 is upwardly, as shown by the arrows, until it enters the chamber 4 and passes thence through the lateral openings 6 into the chamber 5, the passage of the vapor through the pipe 7 is downwardly, as shown by the arrows, through both of the vertical portions of said pipe until the lowermost curved part of the pipe is reached, where the same is provided with a nozzle 21 into which is screwed a burner tip 8 having therein a passage 9 which terminates in a small perforation 10 at the upper end, through which small or fine opening the vapor is ejected under the pressure which drives it forward.

This tip 8 being screw-threaded is adjustable and removable, as is indicated in Figs. 1 and 2. The relative size of the passages 9 and 10 may vary as may also the way in which the tip is inserted and mounted and adjusted, great liberty in respect to the de-

tails of the burner tip as well as other parts being permitted.

The casting 20 has a central circular opening 22 immediately above the burner tip 8, 5 and said opening receives a cylindrical member 15 having a flange 23 thereon which rests loosely upon the edge of said circular opening 22 and is in this way supported by the horizontal casting 20. Said cylindrical member 15 extends for a certain distance 10 above the casting 20 and is provided below its cylindrical section with a conical or downwardly flaring section 14 which terminates in a tubular section 11 of smaller 15 diameter than the cylinder 15, said tubular section 11 being provided with two or more perforations or openings 12, and surrounding the tubular member 11 is a sleeve 24 having perforations or openings 13 which 20 register with the perforations or openings 12 but can be adjusted relatively thereto so that the registry may be partial or complete as desired, and through these openings 12 and 13 and also through the lower open end 25 of the tubular member 11 air is introduced from the outside atmosphere, being sucked in by the upward rush of the vapor from the tip 8 which draws in the air along with it, as shown by the arrows. In this way a large 30 volume of vapor is carried upwardly into the cylinder 15 and discharged at the upper end of the same against the top or cover 16 which is a casting having a central member that lies at a suitable distance above the 35 upper periphery of the cylinder 15 and is integral with an annular flange 25 which stands within a short distance of the upper periphery of cylinder 15 and is integral with an annular plate 18 which is supported upon 40 the casting 20 by means of a few feet consisting of pins 17. The outer periphery of this annular plate 18 is spaced a short distance from a ring 19 which rests loosely upon the outer peripheral edge of the casting 45 20, being suitably indented near its lower edge to allow it to engage and rest upon said casting 20, as is clearly shown in Figs. 1 and 2. By means of this construction and combination, therefore, it will be obvious 50 that as the volatilized or vaporized gas rushes upwardly in a vigorous way as an ascending column it will strike against the top or cap which will serve as a baffle plate and will direct it sidewise so that it will 55 flow through the space between the wall 25 and the edge of the cylinder 15, passing then downwardly underneath the annular plate 18 and being directed upwardly and outwardly by the ring 19 so that an annular 60 ring of gas will be ejected between the edge of the plate 18 and the ring 19. At this point the gas is ignited and the flame created, which latter will have a circular form and will spread upwardly and outwardly with a 65 large and intense volume of heat, the com-

bustion being promoted and perfected by the supply of air and by the highly vaporized character of the gas which is due to the way in which the vaporization is effected.

The operation of my improved vaporized oil burner will be readily understood from the foregoing description of the construction and arrangement of the different parts. The use of a certain amount of priming fluid in the cup 2 will heat the upper portion of the burner exceedingly hot so that when the oil rising through the pipe 3 comes into contact with the heated pipe and also with the other heated parts above, it will flash into vapor and this vapor will first 70 enter the chamber 4; it will pass thence into chamber 5 and there be superheated, which will more completely convert it into a fine volatile condition, after which it will continue through the pipe 7 and emerge from 75 the burner tip 8 through the minute orifice therein in a very fine spray, which will rush upward with great speed, drawing the air along with it, which enters in the lower end of tube 11 as also through the openings 12 80 and 13 whereby a complete mixture of air with the gas will occur, said mixture rising up against the top member 16 and being deflected thereby to the ignition point around the periphery of ring 19 will supply a 85 highly inflammable gas and provide an effective flame for heating for any purpose for which it may be desired. While I have invented and devised and planned this burner for use in connection with brooder 90 stoves, I do not intend to have it confined thereto, as it has a wide range of practical application.

Having thus described my invention, what I claim as new and desire to secure by Letters Patent, is:

1. In an oil burner, the combination of a primary vaporizing chamber having an inlet for the vapor, a superheating chamber communicating with the primary chamber, 110 a bow-shaped tube supported by said superheating chamber and having an outlet for the vapor, a tip supported at said outlet and having a constricted orifice, a mixing device for the gas and air loosely supported 115 on the superheating chamber above said tip and having a conical portion and a tubular lower end provided with a valve, and a top supported above said mixing device for spreading the mixture outwardly at the ignition point.

2. In an oil burner, the combination of a primary vaporizing chamber having an inlet for the vapor, a bow-shaped tube entering 125 said inlet, a superheating chamber communicating with the primary chamber, a bow-shaped tube for carrying the vapor from the superheating chamber, an outlet on the central portion of said latter tube, a burner device on said outlet having a constricted 130

orifice, a mixing chamber loosely supported on the superheating chamber and consisting of a flanged cylindrical portion, a conical portion and a lower tubular part, the latter being provided with a perforated encircling valve ring for admitting air into the mixing chamber to be mixed with the ascending vapor.

3. In an oil burner, the combination of a primary vaporizing chamber, means for admitting vapor thereto consisting of a bow-shaped pipe and a supply pipe entering same, a superheating chamber communicating with the primary chamber, a bow-shaped pipe for carrying the vapor from the superheating chamber, a burner device on the latter having a constricted orifice, a flanged mixing chamber loosely supported on the superheating chamber above the said device and provided with an adjustable valve, for admitting air thereinto to be mixed with the ascending vapor, and a deflecting cover loosely supported above said mixing chamber and upon the primary vaporizing

chamber, together with a ring loosely surrounding said cover and spaced from its periphery.

4. In an oil burner, the combination of a supply means, a primary vaporizing chamber, a bow-shaped tube between the supply means and said chamber, a superheating chamber receiving vapor from the primary chamber and having an outlet, means for providing a fine passage for the vapor to pass out of said outlet, a mixing chamber supported above the said fine passage and consisting of a cylindrical portion, a conical portion and a lower tubular portion, the latter having means for admitting air thereto so that the vapor and air may be commingled in the cylinder, a plate supported loosely above the mixing chamber and spaced therefrom, and a ring loosely surrounding said plate and spaced from its periphery.

In testimony whereof I hereunto affix my signature.

JOHN F. MacKAY.
